METAL STORM WINDOW

Paul E. Metts, Crafton, Pa., assignor to Aluminum Products Corporation, Pittsburgh, Pa., a corporation of Pennsylvania

Application August 23, 1946, Serial No. 692,407

1. Claim. (Cl. 189—64)

This invention relates to a storm window and, in particular, to a metal storm window characterized by tightly sealed joints, great durability and relatively low cost of manufacture.

Storm windows in various designs and styles and of metal as well as wood construction have been proposed heretofore. All types of such windows with which I am familiar, however, are open to several objections. Wood storm windows are generally not capable of effectively excluding outside air because the joints cannot be tightly sealed. In addition, they deteriorate under weathering. Metal storm windows as previously known have been quite costly. Also, the construction usually employed is such that replacement of a broken pane requires that the sash be returned to the factory. Still further, the sash proper, without glass, lacks rigidity and any stress applied is resisted partly by the glass increasing the likelihood of breakage thereof.

I have invented a novel construction of storm window whereby the above shortcomings of previous designs are largely overcome or eliminated. In a preferred embodiment, my window comprises a continuous unitary frame adapted to fit over the window opening in a building and be permanently secured thereto. The frame has a sash removably mounted therein including upper and lower sections which may readily be removed for cleaning. I also provide a screen adapted to replace the lower section of the sash during warm weather. I make special provisions for sealing the joints between the sash and the frame and between the two sections of the sash. I also provide removable retainer strips for holding the panes in the sash sections whereby replacement of a broken pane may be effected by the average householder without special tools. The frame comprises a head rail, side rails and bottom rails having channels on their inner faces. The sash sections comprise top, side and bottom rails of channel bar having sealing flanges adapted to cooperate with the channels in the frame rails. The rails of the frame and sash are preferably cut from stock extruded from aluminum or other light metal, and I provide novel means for assembling them rapidly and at low cost.

A complete understanding of the invention may be obtained from the following detailed description which refers to the accompanying drawings illustrating a preferred embodiment. In the drawings,

Figure 1 is an elevation of the storm window of my invention from the outer side;

Figure 2 is an exploded isometric view of the frame showing the side rails in transverse section;

Figure 3 is an isometric view of a leaf spring secured to the frame to hold the upper sash section in proper position;

Figures 4 and 5 are similar views showing locking levers for securing the lower sash section in position;

Figure 6 is a partial section taken along the plane of line VI—VI of Figure 1 showing the manner of securing the frame to the edge of a window opening in a building;

Figure 7 is an elevation of the upper sash section looking on the outer side thereof;

Figures 8, 9 and 10 are partial isometric sections taken along the planes of lines VIII—VIII, IX—IX and X—X, respectively, of Figure 7;

Figure 11 is an exploded view of the upper sash section without the glass pane;

Figure 12 is an isometric view showing the details of an angle bracket used to connect the rails of the sash sections;

Figure 13 is an elevation of the lower sash section from the outer side;

Figures 14, 15 and 16 are partial isometric sections taken along the planes of lines XIV—XIV, XV—XV and XVI—XVI of Figure 13;

Figure 17 is an exploded view of the lower sash section without the glass;

Figure 18 is a partial isometric section taken along the plane of line XVIII—XVIII of Figure 1 showing the relation of the meeting rails of the two sash sections;

Figure 19 is an elevation of a screen adapted to be substituted for the lower sash section, looking from the outer side;

Figures 20, 21 and 22 are partial isometric sections taken along the planes of lines XX—XX, XXI—XXI and XXII—XXII of Figure 19; and

Figure 23 is an exploded view of the screen frame.

Referring in detail to the drawings and, for the present, to Figures 1 through 6, the storm window of my invention comprises a frame 10 having a sash 11 including upper and lower sections 12 and 13 removably seated therein. The frame comprises a head rail 14, side rails 15 and a bottom rail 16. These rails are metal bars of suitable thickness having integral sealing channels and are preferably extruded from aluminum or other light metal. The head rail 14 has a downwardly facing sealing channel 17 formed integral therewith. Each of the side rails has an inwardly facing sealing channel 18 extending therealong and the bottom rail 16 has a sealing channel 19 formed at its upper edge. The head rail and side rails are grooved as at 20 to increase their rigidity and improve their appearance.

The side rails are notched or mortised as at 21

to receive the ends of the head rail and the rails are bolted together with the inner corners of the head rail overlying the inner corners of the side rails. A finish plate 22 is secured over the adjacent ends of the head and side rails to conceal the joint. The lower ends of the side rails are bolted to the ends of the bottom rail in overlapping relation, the sealing channels 18 of the side rails being cut away to the extent necessary to permit assembly of the rails in this relation. The bottom rail has ventilating louvers 23 formed therein. A slide 24 movable between guides 25 formed on the inner face of the bottom rail may be adjusted to overlie the louvers to the desired extent, thus affording easy control of the amount of ventilation.

The width of the rails of the frame beyond the sealing channels is sufficient to accommodate minor variations in the size of window openings from nominal dimensions. The installation of the frame is accomplished merely by placing it in the window opening and securing it to the edges thereof by screws 26, as shown in Figure 6, the side rails having holes punched therein at intervals for this purpose. The dimension *d* in Figure 6 indicates the permissible tolerance in all directions from the minimum size of window opening which will accommodate a frame of given dimensions.

The frame 10 is provided with leaf springs 27 of H shape shown in detail in Figure 3 adapted to engage the sides of the upper sash section 12. The frame is also provided with locking levers 28 and 29 pivoted thereto for retaining the lower sash section 13 in position. The levers are shown in detail in Figures 4 and 5. The springs 27 and levers 28 and 29 are secured to a flange 30 extending outwardly from the outer wall of the sealing channels 18.

The sash sections 12 and 13 are of generally similar construction but each will be described separately in detail. The upper section 12, as shown in Figures 7 through 12, comprises a top rail 31, side rails 32 and a bottom or meeting rail 33 composed of channel bars assembled to form a rectangular frame for a glass pane 34. The sections of the channel bars are shown clearly in Figures 8 through 10. All the bars have a web 35 and flanges 36 and 37. Secondary flanges 38 extend inwardly from the flanges 36 and 37. A flange 39 extends inwardly from the flange 36 to provide a seat for the pane 34. The web 35 of the several channel bars is slotted on its inner side as at 40 to accommodate a retaining strip 41 having the general shape of a Z bar in section. It will be observed in Figures 8 through 10 that the slot 40 receives one flange of the retaining strip while the other extends inwardly of the edge of the pane to retain it against the flange 39. The outer edge of the web of the strip has a bead 41a to facilitate removal of the strip by a prying instrument such as a screw driver. A sealing and cushioning gasket strip 42 of cork or the like is disposed between the retaining strip and the pane.

The channel bars of which the rails of the sash section are formed are beveled at their ends and are secured together by angle brackets 43, one of which is shown in Figure 12. These brackets have legs disposed at right angles and notched on opposite sides as at 44. The legs of the angles extend into the slots in the channel bars defined by the web 35, the flanges 36 and 37 and the secondary flanges 38. When the bars have been assembled with the angle brackets in

this manner, the secondary flanges are deformed by suitable dies to cause the metal thereof to flow into the notches 44 to a limited extent, thereby providing a positive mechanical lock 5 which holds the rails of the sash section permanently and rigidly in assembled relation. The bar forming the top rail 31 has a stiffening flange 45. The bars forming the side rails have a sealing flange 46 of angle section. The bar forming the bottom rail 33 has an outer sealing flange 47 and an inner sealing flange 47a.

The upper sash section is dimensioned so that when it is placed against the inner face of the frame, the sealing flanges 46 on the side rails 32 will be in alignment with the channels 18 on the side rails of the frame. When the sash section is thus positioned, it may easily be pushed upwardly until the top rail enters the channel 17 on the head rail of the frame after which the lower portion of the sash section may be moved outwardly until the flanges 46 enter the channels 18 throughout the full length of the former. The springs 27 tend to urge the sash section away from the frame but it is held in place against the spring pressure by the lower sash section 13 when put in place and locked by the levers 28, as will be apparent from the detailed description thereof given herebelow. It will be evident from the description so far that the top rail 31 of the upper sash section makes tight sealing engagement with the channel 17 on the head rail of the frame and that the sealing flanges 46 on the side rails of the sash section similarly have tight sealing engagement with the channels 18 on the side rails of the frame.

The lower sash section 13 shown in Figures 13 through 17 is generally similar to the upper section 12 in that it is composed of a top rail 48, side rails 49 and a bottom rail 50. The side rails 49 and the bottom rail 50 are composed of channel bars of the same section as the side rails 32 of the upper sash section. The top rail 48 is composed of a channel bar similar to that forming the top rail 31 of the upper sash section except that the former has an upwardly extending flange 51 instead of the downwardly extending flange 45. The rails of the upper sash section are secured together by angle brackets 43 and a glass pane 52 is seated therein and secured by retainer strips 41 in the manner already described.

When the upper sash section has been installed as explained above, the lower section may be put in place by disposing the flange 37 of the top rail 48 against the flange 36 of the bottom rail 33 of the upper sash section. The lower portion of the lower sash section may then be swung inwardly until the sealing flanges 46 on the side and bottom rails enter the channels 18 in the side rails of the frame and the channel 19 in the bottom rail thereof. The levers 29 may then be turned down to hold the lower sash section in position. As shown in Figure 18, the flange 51 of the top rail of the lower sash section makes sealing engagement with the flange 47a of the bottom rail of the upper section. Similarly, the flange 47 of the bottom rail of the upper section makes a tight joint with the web 35 of the channel bar forming the top rail of the lower section. This web has a rabbet 53 to receive the flange 47, the depth of the rabbet being less than the thickness of the flange whereby the latter overhangs so as to permit free drainage of rain water. Since the several rails of the sash sections are made of extruded stock which may be kept within very close dimensional tolerances, a precision fit of the meeting

70 rails of the sash sections are made of extruded stock which may be kept within very close dimensional tolerances, a precision fit of the meeting

rails 33 and 48 is assured and infiltration of air through the joint therebetween is reduced to practically nil. The springs 27 force the upper sash section inwardly to maintain the flange 47 in close contact with the web 35 without impairing the sealing relation of the flanges 46 of the upper section with the channels 18 on the frame.

Figures 19 through 23 show a screen 54 adapted to replace the lower sash section 13. The screen comprises a frame including a top rail 55, side rails 56 and a bottom rail 57 held in assembled relation by means of angle brackets 43 in the same manner as the sash sections. The top rail 55 is formed from channel bar generally similar to that used for the top rail 48 of the lower sash section except that it does not have the sealing flange 51 and has a channel 58 on the inner side thereof adapted to receive the edge of a panel 59 of wire mesh and a binder rod 60. The side rails 56 and bottom rail 57 are composed of a channel bar similar to that used for the side rails 32 and 49 except that they are provided with the channel 58 instead of the flanges for the glass pane to seat against. When the rails 55, 56 and 57 have been assembled, the screen may be completed by laying the panel of wire mesh thereon and pressing the binder rods 60 into the channels 58. It will be understood that the edges of the panel lap the channel 58 so as to be tightly held by friction when the rods are pressed home. The mesh panel may be replaced whenever necessary by prying out the rods 60. It will be apparent that the screen 54 has means for tightly sealing all joints between it, the frame 10 and the upper sash section 11, thereby precluding the entry of even the smallest insects.

The storm window of my invention, as will be evident from the foregoing, has numerous advantages over storm windows as constructed heretofore. In the first place, the frame and sash sections are all metal, except for the glass panes, thereby eliminating warpage, shrinkage or the like, and permitting manufacture to desired dimensions within small tolerances. In addition, the all-metal construction has a long life, showing little or no deterioration after extended use. The frame is factory-made in proper sizes so there is no cutting or fitting on the job. The wide lap of the frame over the edges of the window opening permits a single size of frame to be tightly fitted to window openings in a range of sizes; thus a few stock sizes of frames can be adapted for practically all standard sizes of windows. The fabrication of frames and sash sections to special order is but a simple matter, however, since the only variable is the length of the side, top and bottom rails and the size of the panes.

The angle bracket used to connect the rails of the sash section provides a rigid construction which may be assembled quickly and easily. The rigidity of the resulting frame protects the glass pane from twisting stress. The removable retainer strips make it possible to replace broken glass very easily and the gasket strips prevent leakage of air around the edges of the panes. The joints between the frame and sash sections are closed by baffle or labyrinth seals, reducing infiltration to a minimum, providing effective weatherstripping of the sash.

The invention may be applied to buildings of any construction, i. e., frame, brick, stone or stucco. Finally, my construction permits easy removal and replacement of the sash sections for cleaning and replacement of the lower sash by 75

a screen during warm weather. Accurately controlled ventilation is obtainable by the slide 24 when both sash sections are in place.

Although I have illustrated and described but a preferred embodiment of the invention, it will be recognized that changes in the details and arrangement disclosed may be made without departing from the spirit of the invention or the scope of the appended claim.

I claim:

In the combination of a frame with a plurality of glazed sash panels mounted therein in substantially coplanar abutting relationship, the sash panels being in slidable engagement with the sides of the frame and being removable from the frame in a direction normal to the plane of the frame, the improvement comprising a pair of opposite parallel side members of the frame each in the form of an integral length of extruded metal having a first flange extending parallel to the plane of the frame and two other flanges projecting from one side of the first flange normal to the plane of the frame and forming a channel therebetween, said first flange having a flat surface of substantial area on said one side between the outer edge of the first flange and the nearer of the other two flanges, and a pair of opposite parallel side members of each sash panel slidably engageable with the respective frame members and also each in the form of an integral length of extruded metal, each of said sash panel members having a flat portion of substantial area slidably bearing against said flat surface of the first of said flanges of the adjacent frame member, and having a flange of substantially U-shaped cross section extending around both sides of one and along one side of the other of the said other two flanges of the adjacent frame member, with the U-shaped flanges of the sash panels extending from and between the front and rear planes of the sash panels and with the outer edges of the interlocking flanges of the sash panels and frames spaced from any sliding contact during relative movement of the sash panels in the frame, whereby the said flanged frame and sash panel members form a rigid and weather-tight window structure with the wear distributed along the sides of the flanges to increase the life of the structure.
